UNITED STATES PATENT OFFICE.

VICTOR G. ELLIS, OF NEW YORK, N. Y., ASSIGNOR TO HIMSELF, HARRY PHILIP HAGELSTEIN, AND CHARLES WILLIAM HAGELSTEIN.

MOTOR SUSPENSION.

Application filed January 15, 1921. Serial No. 437,490.

To all whom it may concern:

Be it known that I, VICTOR G. ELLIS, a citizen of the United States, and resident of the borough of Manhattan, city, county, and State of New York, have invented certain new and useful Improvements in Motor Suspension.

This invention relates to improvements in motor suspension and its principal object is to provide a means whereby the weight of the motor is utilized to maintain the driving belt in tension thereby eliminating the necessity of providing separate tension devices.

Another object of the invention is to provide a device which may be hung from a suitable support or may be reduced to stand upon a support without in any way impairing its operation.

Still another object of the invention is to provide a novel means for swingably securing the motor supporting frame in such a manner as to prevent it from becoming disengaged from the support.

A further and more specific object of the invention resides in the provision of an adjustable supporting means for the motor supporting frame.

With these and other objects in view the invention consists in the novel construction, combination and arrangement of parts which will be fully set forth in the following specification, claimed and illustrated in the accompanying drawings in which:

Fig. 1 is a perspective view of this improved motor suspension.

Fig. 2, is a side view of a portion thereof showing the device supported from below.

Fig. 3, is a side view of the modified form of motor suspension and

Fig. 4, is a perspective view of an adjustable supporting element used in conjunction with the device.

Referring to the drawings in detail the numeral 5 designates the hanger or supporting element constituting a substantially inverted U-shaped member 6 having extending horizontally between its arms a bar 7 which constitutes the hanger bar upon which

the device is swingably supported. A spacer 8 is adapted to fit around the bar 7 at a point intermediate its ends and secured to said spacer is a plate 9, the opposite extreme ends 10 of which project beyond the

ends of the spacer 8 for a purpose to be more fully hereinafter described. A set screw 9 is passed through the plate 9 and spacer 10 and engages the bar 7 to prevent sidewise movement of the spacer and the hooks.

The motor 11 is supported in a substantially rectangular frame 12 having secured to its rear side standards 13, the extreme ends of which are bent as at 14 to provide hooks for engagement over the hanger bar 7. It will be understood that the extreme inner edges of the hooks 14 engage the ends of the spacer 8 and when in this position it will be obvious that the ends 10 of the plate 9 will partially overlie the hooks 14 and prevent said hooks from jumping out of engagement with the bar 7.

Formed on the standards 13 in spaced relation to the hooks 14 are oppositely turned hooks 15 which are adapted to engage the hanger bar 7 when the device is used as illustrated in Fig. 2.

In order to limit the swinging movement of the device, a bar 16 is adjustably secured in straps 17 to the front of the frame 12 and its upper end is provided with a hook 18 which is adapted to be received in a yoke 19, which may be attached in any suitable manner to a stationary support. It will thus be obvious that should the belt 20 break or slip off of its pulley, the motor will tend to swing downwardly around the bar 7 and the length of movement will be limited by the engagement of the hook 18 with the yoke 19.

In the modified form of the device illustrated in Fig. 3, the motor 21 has secured to its base plate suitable standards 22 which are provided with yokes 23 and 24 corresponding respectively with the yokes 14 and 15 of the standards 13. These yokes are adapted to engage the hanger bar 7 mounted in the hanger 5, and the same means as previously described is used for securing the hooks against accidental displacement. In this type of device it will be seen that should the belt 25 break, the motor will be free to swing and no limiting device is used.

In the modified form of hanger illustrated in Fig. 4, a suitable U-shaped stationary member 26 is provided and an adjustable U-shaped member 27 is pivotally supported on suitable bolts 28 between the arms of the member 26. The hanger bar 29 is secured to and extends between the arms of the mem-

ber 27 and it will be obvious that by adjusting the tension of the bolts 28 the device may be held in various adjusted positions.

In use the device is supported in the manner shown and it will be obvious that when a load is placed on the belt 20, the belt will be held under tension by the weight of the motor thereby avoiding the necessity of providing separate tension devices and since the load ordinarily varies according to the number of machines in operation it will be seen that the motor will be free to swing back and forth and yet at all times will maintain sufficient tension on the belt to drive the mechanism.

While in the foregoing there has been shown and described a preferred embodiment of this invention it is to be understood that certain minor changes in the details of construction, combination and arrangement of parts may be resorted to.

What is claimed is:—

1. Means for supporting a belt operating member comprising a supporting bar, hooks suspended from said bar, a housing for said belt operating member supported by said hooks, and a yoke and a hooked bar for

limiting the movement of said housing and straps upon said housing, in which said bar is adjustably secured.

2. A mounting for a belt operating motor which comprises a housing for said motor, a support for said housing comprising a bracket, a rod in said bracket, hook members connecting said rod and said housing, said hook members being suspended from and adapted to have movement around said rod, and a plate associated with said rod for preventing the accidental disengagement of said hook members and means for limiting the swinging movement of said housing.

3. A mounting for a belt operating element which comprises a housing therefor, a supporting rod, hook members suspended from said rod and connecting said housing and said rod, said housing being adapted to swing about said rod, means for limiting said swinging movement, a spacer for preventing movement of said housing longitudinally of said rod, and a plate for retaining said hook upon said rod.

Signed in the city, county and State of New York, this 22d day of December, 1920.

VICTOR G. ELLIS.
